UNITED STATES PATENT OFFICE

163,251

RADIOTELEGRAPH KEY

Bernard H. Breedlove, Atlanta, Ga.

Application December 1, 1950, Serial No. 13,232

Term of patent 14 years

(Cl. D26—14)

To all whom it may concern:

Be it known that I, Bernard H. Breedlove, a citizen of the United States, residing at Atlanta, Georgia, have invented a new, original, and ornamental Design for Radiotelegraph Key, of which the following is a specification, reference being had to the accompanying drawing, forming a part hereof.

Fig. 1 is a top plan view of the radiotelegraph key showing my new invention.

Fig. 2 is an elevational view of the radiotelegraph key shown in Fig. 1 as seen from the front side.

Fig. 3 is an end elevational view of the radiotelegraph key of Fig. 2 as seen from one end thereof; and Fig. 4 is an end elevational view of the radiotelegraph key as seen from the end opposite to the end shown in Fig. 3.

Fig. 5 is a bottom plan view of the radiotelegraph key of Fig. 1.

Fig. 6 is an elevational view of the radiotelegraph key of Fig. 1 as seen from the rear side.

Fig. 7 is a three quarter perspective view of the radiotelegraph key as seen from above.

I claim:

The ornamental design for a radiotelegraph key, as shown.

BERNARD H. BREEDLOVE.
